UNITED STATES PATENT OFFICE.

JOSEPH ROSENBLATT, OF PROVIDENCE, RHODE ISLAND.

EYEGLASS-MOUNTING.

1,322,624.

Specification of Letters Patent. Patented Nov. 25, 1919.

Application filed December 15, 1916. Serial No. 137,097.

To all whom it may concern:

Be it known that I, JOSEPH ROSENBLATT, a citizen of the United States, and resident of the city of Providence, in the county of Providence and State of Rhode Island, have invented certain new and useful Improvements in Eyeglass-Mountings, of which the following is a specification.

This invention relates to mountings for 10 eyeglasses, spectacles and the like and relates more particularly to means for securely fastening the lens in the mounting.

The primary object of my invention is the provision of means whereby when the 15 screw is brought to its seat the same is securely locked in that position against being accidentally withdrawn.

A further object of the invention is the provision of means whereby the act of finally 20 positioning the binding member such as a screw or rivet through the ear and lens serves to seat the lens tightly against the saddle portion of the clip.

With these and other objects in view, the 25 invention consists of certain novel features of construction, as will be more fully described, and particularly pointed out in the appended claims.

In the accompanying drawings:

30 Figure 1— is a side elevation showing a portion of the lens held in its clip and a screw having an eccentric head adapted to engage a correspondingly shaped opening in the clamp ear whereby when rotated to 35 position it draws the saddle firmly against the edge of the lens, this head being also shown as provided with my improved locking means.

Fig. 2— is a section of the lens clip showing the particular form of screw illustrated in Fig. 1 in position in this clip.

Fig. 3— is a side elevation showing a raised cam-shaped member on the lens strap or ear engaged by a protuberance on the side 45 of the screw head for the purpose of drawing the clip against the edge of the lens and simultaneously locking the screw in seated position.

Fig. 4— is a sectional edge view of the 50 structure illustrated in Fig. 3.

It should be clearly understood that in this invention the essential feature is the provision of a lock in the screw which does not depend on the drawing of the two lens 55 clamp ears toward each other, but rather one

that acts in line with the horizontal axis of the lens, which construction needs no particular space to be left between the ears and lens, to permit my lock to operate as in rotating my screw to its seat the lens is 60 drawn toward its saddle.

In carrying out my invention, 10 designates the nose bridge member which joins the two lens straps or clips 11. Each clip is provided with a saddle portion 12 and in 65 some cases a pair of side or clamping ears 41 between which the lens 14 is held. In other instances but one of these ears 41 is employed, the opposite ear being removed as illustrated in Fig. 2 for purposes herein- 70 after described while in other cases two ears are employed as illustrated in Fig. 4.

One of the features of my lens clip is the means whereby I force the edge 15 of the lens against the saddle portion 12 by 75 the positioning of the screw 32 through the ear and lens.

One simple means for accomplishing this longitudinal relative movement of the lens and clip is illustrated in Figs. 1 and 2 in 80 which the head portion 31 of the screw 32 is formed eccentric to the axis of the screw, whereby when the screw is forced home this eccentric engages a correspondingly eccentric opening 33 in the strap and forces the 85 edge of the lens to a seat 15 in the saddle 34.

The edge of this screw is shown as being flattened as at 35 for the purpose of engaging a correspondingly flat face 36 of the raised portion 37 on the ear 38.

Another means of providing a relative endwise movement of the lens and clip is to provide an abutment 39 on the lug 40 of the ear 41, see Fig. 3, which abutment is engaged by a protuberance 42 on the edge of the screw head 43, which structure performs two functions: first, to produce a relative endwise movement of the lens and clip and also to cause this protuberance to engage a recess 44 in the raised portion 40 for the purpose of providing a lock to prevent a rotation of the screw after having been forced to its seat.

A clip having but one ear as illustrated in Fig. 2 is also well adapted to receive lenses 105 of different thicknesses.

I have illustrated a number of means whereby my invention may be carried out, but I do not wish to limit myself to any of these specific constructions as various 110

changes in shape and form of the several features may be necessary. I therefore desire it to be understood that I reserve the privilege of resorting to all the mechanical changes to which the device is clearly susceptible, the invention being defined by the terms of the appended claims.

I claim.

1. A lens clip comprising an ear provided with a counterbore having a protuberance at its periphery substantially in line with the horizontal axis of the lens, a binding screw passing through said ear and lens, said screw being provided with a flattened portion on one side only of its head to engage said protuberance on the ear whereby a tension is exerted between the ear and screw as the latter is turned to its seat to prevent the screw from loosening.
2. A lens clip comprising an ear provided with a counterbore having a flattened portion extending within the circle of said bore substantially in line with the horizontal axis of the lens, a binding screw passing

through said ear and lens, the head of said screw being cut away and correspondingly flattened on its periphery to engage said flattened portion on the ear, whereby a tension is exerted between the ear and screw in turning the latter to its seat to prevent loosening of the screw.

3. A lens clip having an ear provided with a counterbore and having a member raised above the plane of the ear on the periphery of said counterbore, said raised portion being substantially in line with the horizontal axis of the lens, a binding screw passing through said ear and lens, said screw being provided with a flattened portion on one side only of its head to engage said raised portion on the ear when said screw is being turned to its seat to prevent the screw from accidentally turning backward.

In testimony whereof I affix my signature in presence of a witness.

JOSEPH ROSENBLATT.
